Primary Examiner—James Gandy**Assistant Examiner**—Stacia Sinuik**Attorney, Agent, or Firm**—Thompson Hine & Flory LLP**[57] CLAIM**

The ornamental design for a vehicle wheel front face, as shown and described.

DESCRIPTION

FIG. 1 is a front perspective view of my new vehicle wheel front face; and.

FIG. 2 is a front elevational view thereof.

The broken lines shown in FIG. 1 and in the central hub area of FIG. 2 of the drawings are for illustrative purposes only and the subject matter depicted thereby constitutes no part of the claimed design.
